UNITED STATES PATENT OFFICE.

WILLIAM O. ALDRICH, OF WHITINSVILLE, MASSACHUSETTS, ASSIGNOR TO WHITEN MACHINE WORKS, OF WHITINSVILLE, MASSACHUSETTS, A CORPORATION OF MASSACHUSETTS.

FLIER.

1,426,443.

Specification of Letters Patent. Patented Aug. 22, 1922.

Application filed August 26, 1920. Serial No. 406,165.

To all whom it may concern:

Be it known that I, WILLIAM O. ALDRICH, United States citizen, residing in Whitinsville, Worcester County, State of Massachusetts, have invented the following described 5 Improvements in Fliers.

My invention relates to the art of making fliers of the kind used on the spindles of roving frames and which comprise a central hub structure and two legs depending therefrom without other support, and has particular reference to the cost of manufacture of this class of fliers. The invention resides in the essential idea of uniting the separately 10 formed leg and hub members by means of a sheet metal crown or shoulder piece pressed or formed to a special shape and welded or otherwise secured to the legs and hub so as to produce a built-up flier equivalent to the one-piece hand-forged article now commonly used. Commercial manufacture of fliers has been heretofore confined to the hand-forged process which, though laborious and expensive, has been generally conceded to be 15 the only satisfactory method of obtaining that combination of rigidity and permanency of balance that is demanded by practical service. Various proposals to forge only the crown and hub parts out of a single piece of 20 stock, thereafter affixing the legs to it, have been found in practice to be quite as expensive as to forge the whole flier from a single piece and so far as I am aware, various proposals to form the flier wholly from 25 sheet metal have failed in practice either because of the inherent weakness of such fliers, or the expense and complication of their 30 manufacture.

According to my invention each of the 35 component members of the flier is designed and adapted for economic manufacture, the crown piece in particular being specially formed to that end and adapted for rapid and accurate assembly with the other members so that the completed structure can be 40 practically produced at a low cost and generally less than half of the cost of forged fliers.

In the drawings—

Fig. 1 is a side elevation of the preferred 45 form of this invention;

Fig. 2, an elevation of the partly completed hollow leg, showing the yarn slot;

Fig. 3, the completed leg;

Fig. 4, an axial section of the hub;

Fig. 5, a cross-section thereof;

Fig. 6, the crown blank;

Figs. 7, 8 and 9, side, section and plan views of the first stamping of the crown;

Figs. 10 and 11, plan and longitudinal section views of the completed crown;

Fig. 12, a section of the flier through the plane of the legs; and

Fig. 13 an end elevation of the crown.

The leg 1 is a solid rod, preferably of oval cross-section, and is produced by simply cutting off a length of bar stock. The opposite leg 2 is formed by rolling up a flat sheet-metal blank of substantially the shape shown by the dotted lines in Fig. 2, and producing 70 thereof a tapered hollow leg with an open crevice 3 between the meeting edges of the blank, which crevice forms the yarn slot. The hollow leg is then twisted so as to distort the yarn slot and give it the curved 75 shape shown in Fig. 3. It will be understood that the yarn slot 3 is for the introduction of the yarn into the leg and requires to be non-rectilinear in order to prevent the escape of the yarn under the centrifugal effect. As 80 thus shaped, the hollow leg with the curved yarn slot is supplied with a pair of nibs or projections 4 to support and retain the band 5 of the yarn guide and presser. These nibs 85 can be bossed up from the leg blank if desired, or struck up as tabs therefrom in any suitable way, but I find it practical and quite as economical to make them as separate parts and solder or spot-weld them to the leg as shown in Fig. 1. All these operations on 90 the hollow leg are simple and readily performed by the aid of simple machinery. The presser comprises the band 5, the counter-weight limb 6, and the usual arm and pad 7, being quite the same as the common presser 95 on the forged flier.

The hub 8 is first made of circular section, preferably throughout, and is therefore an automatic machine job, that is to say, it is adapted to be produced at low cost in one of 100 the well known types of automatic turret lathes, such machines being capable of taking in the blank stock at one end and delivering the hubs in substantially finished form at the other end. The hub comprises a tubular body provided externally with a flange 9 near its upper end and internally with a taper-socket to receive the tapered tip of the spindle, and it is also cross-bored at 10 to receive a cross-pin. The flange 9, being ini- 105

tially circular, is slabbed off as indicated at 11 in Fig. 5, and a yarn outlet 12 is formed above the flange. These several operations on the hub member are manifestly low cost operations and largely automatic.

The remaining part of the flier is the crown or shoulder piece 13 which unites the two legs to the hub and according to this invention can also be made with no greater difficulty than the other parts. In its preferred form and as herein shown, it is the product of simple stamping and punching operations capable of performance with rapidity and at low cost, and has such shape in respect to its vertical dimensions as to possess well defined characteristics of girder construction with attendant strength and lightness of weight and such vertical dimensions afford an attachment area for the legs and hub which is ample for maintaining them in their accurate relative positions, even prior to their final and permanent attachment, thereby assisting the attachment process. The flat blank 14 of Fig. 6 is first stamped into the cupped and bow-shaped form shown in Figs. 7, 8 and 9 in which, as will be seen in these figures, it has a substantially flat central top wall 15 merging into two downwardly sloping top walls or arms 16 and 17 and flat, substantially vertical side walls 18, and rounded end walls 19 and 20. Its cross-section is that of an inverted U, being wider at the middle and diminishing in width toward the ends, which however are slightly widened to form interior leg sockets as shown more clearly in the plan view of Fig. 9. This shape of crown piece is reached by a single stamping. It will be noted that the crown piece is unsymmetrical, in that the arm 16 (Fig. 7) is slightly longer than the other.

The crown stamping is punched with a center hole 21 in its top wall 15 to receive the hub and with a hole 22 at the end of its top wall 16 and this latter wall is provided with a longitudinal depression or yarn groove or channel 23 leading from near the center to the hole 22 as shown in Figs. 10 and 11. Two opposite cross-pin holes 24 are also punched in its side walls 18. These several punchings can be done in one operation if desired, it being understood that the first rough stamping of Figs. 7-9 can be finally shaped and smoothed up in a set of finishing dies either before or after the punching step just described or coincidently with it.

In the assembly of the foregoing parts the solid leg 1 is pushed into the socket enlargement formed by the end wall 19 and finds a substantial surface contact therein for attachment purposes. The hollow leg 2 is pushed into the similar socket formed by the end wall 20 of the other arm and when so placed its interior passage registers with

the hole 22 and its shouldered edge 25 abuts against the lower side of the depressed yarn groove 23 as indicated in Fig. 12; at the same time this leg, being somewhat resilient because of its yarn slot fits snugly in its 70 socket with a very considerable surface contact with the interior of the socket. In these positions the legs are easily secured to the crown by welding or brazing, and preferably by electrically spot-welding them to 75 the side and end walls which results in a practically rigid connection between the legs, maintaining them accurately in their desired relation and serving also to stiffen the hollow leg against any change of shape. 80

The hub 8 is introduced into the central opening so that its flange 9 abuts against the underside of the central top wall 15 and its slabbed edges 11 fit against the adjacent parts of the side walls 18. In this position 85 it is welded to the crown as in the case of the legs, and further secured thereto by a cross pin 26 which is driven and riveted into the registering holes 10 and 24 so that it traverses the upper end of the taper socket so as 90 to serve also as a key for the end slot in the spindle tip, the flier being of course freely removable from the spindle. The flier is finished by slotting the end wall 20 as indicated at 27 in Fig. 13 in continuation of 95 the yarn slot 3, and then the whole structure is lapped and polished and when the presser has been applied is ready for use.

It will be understood that the yarn is threaded as usual through the open upper 100 end of the hub and the lateral yarn outlet 12 and then laid in the yarn groove 23 and passed sideways through the yarn slot 3 and 27 so that it may run through the hollow leg to the guide eye on the presser. The 105 yarn groove 23 is for the purpose of guiding the yarn to the hollow leg and leading it over but not in contact with the edge 25 thereof which, being a cut edge, is not easily smoothed because of its location, and 110 for the same reason the said edge 25 is shouldered down below the top of the leg, as indicated by the shape of the leg blank in Fig. 2. The yarn groove also lends further stiffness to the crown. Inasmuch as 115 the hollow leg is fixed to the longer arm of the crown, its axis is somewhat farther from the axis of the hub than the solid leg, a condition which is found desirable for a proper rotary balance of the structure 120 and avoids increasing the mass of the solid leg, and this particular relation is assured by the method of manufacture above described because the arm length of the crown is absolutely controlled by the shape of the 125 dies in which it is made and is unaffected by any subsequent step of the process so that all the fliers produced in the same set of dies are exactly identical in respect to dimensions and therefore require little or no 130

filing or subsequent change to make the balance perfect.

The open-bottomed and bow-shaped type of crown stamping having the cross-section 5 of an inverted U as above described is found to be the best in practice, but the essential advantage and economy of that form may also be approximated by other crown members stamped, rolled or otherwise built of 10 sheet metal and having the characteristics of a girder in cross-section as above explained, and it will be understood that various modifications, changes, substitutions for and additions to the structure shown in 15 the drawings may also be employed without departure from this invention as set forth in the following claims.

Claims—

1. A flier of the kind described, comprising opposite, separately-formed legs, a 20 crown formed of sheet metal welded to the legs and a separately made hub welded to the crown.

2. A flier comprising a sheet metal stamping 25 constituting a crown with a girder cross-section and two legs, one of which is hollow, rigidly fixed by their ends to the ends of the crown, the other ends of the legs being unsupported, and a separately made hub secured to the crown and adapted to seat on a spindle tip.

3. A flier of the kind described comprising opposite, separately-formed legs, a sheet metal stamping of inverted U cross-section 35 constituting a crown adapted to receive the legs at its ends and being rigidly fixed thereto and a separately made hub secured to the crown.

4. A flier comprising a crown formed from sheet metal and having a yarn slot at 40 one end thereof, a separately formed, hollow leg having a yarn slot secured to the said slotted end of the crown and having its interior passage opening through the crown, a solid leg secured to the other end 45 of the crown and a hub secured in a central perforation in said sheet metal crown.

5. A flier comprising a crown stamped from sheet metal, a solid leg secured to one 50 end of such stamping, a hollow leg having a yarn slot secured to the other end thereof and having its interior passage opening upwardly through the stamping, a hub secured in a central perforation in said stamping and extending above and below 55 the same and a yarn outlet in the hub above the crown.

6. A flier comprising a crown formed from sheet metal with a socket at one end secured to a leg and a socket at the other 60 end secured to a hollow leg having a yarn slot, said crown having a yarn-conducting groove or channel on its upper side leading to the interior of said hollow leg.

7. A flier comprising a sheet metal crown 65 and a hollow leg secured in a socket at one end thereof, a portion of the crown being extended over the edge of the leg and adapted to conduct the yarn to the interior thereof.

8. In an assembled flier a sheet metal 70 crown piece having an inwardly depressed groove serving as the arm guide.

In testimony whereof, I have signed this specification.

WILLIAM O. ALDRICH.
